UNITED STATES PATENT OFFICE.

ORLANDO M. POND, OF INDEPENDENCE, IOWA.

SLATE-FRAME.

SPECIFICATION forming part of Letters Patent No. 298,499, dated May 13, 1884.

Application filed September 21, 1883. (No model.)

To all whom it may concern:

Be it known that I, ORLANDO M. POND, of Independence, in the county of Buchanan and State of Iowa, have invented certain new and useful Improvements in Slate-Frames; and I do hereby declare that the following is a full, clear, and exact description thereof, reference being had to the accompanying drawings, and to the letters of reference marked thereon, which form part of this specification, in which—

Figure 1 is a perspective view of one corner of my improved slate-frame, showing a portion of a slate secured therein. Fig. 2 shows two sections of the frame, adapted to 15 form a right-angle corner. Fig. 3 is a modification.

This invention relates to frames which are designed for school-slates and other purposes; and it consists in a frame which is composed 20 of strips of pasteboard prepared and put together in the manner which will be fully understood from the following description, when taken in connection with the annexed drawings. Each one of the end and side bars of 25 the frame is composed of three narrow strips of pasteboard. The strips A A' are of the same width, and are cemented to an intermediate strip, B, which is narrower than the strips A A', for the purpose of leaving a groove, 30 a, adapted to receive the edge of the slate or other slab. The side and end bars of the frame are united by lapping joints; or, if desired, each portion, A, A', and B, may be made continuous, as shown in Fig. 3, so that the corners of the slate will be solid. When the corners are made with lap-joints, I construct each corner as follows: The end of the strip A of a side bar is extended beyond the strips A' B, 35 a distance equal to the width of the strips A A', so as to form a lapping portion, b, leav-

ing a portion, c, of the intermediate strip, B, extended a short distance beyond the shoulder d, at the terminus of the strip A'. The end bar is constructed to match the parts b c d and form a double lap-joint, the end bar being secured to the side bar by means of any suitable cement. It will be observed, by reference to the right-hand portion of Fig. 2, that the ends of the strips A' B are both extended beyond the shoulder e at the end of the strip A, a distance equal to the width of the strips A A'. Thus it will be seen that one end of a side bar is a counterpart of one end of an end bar, both ends matching exactly, so as to form, when cemented together, a substantial 50 joint, which I prefer to cover with leather D, or other suitable material cemented over the joint, which not only gives a finish to the corner, but renders the slate noiseless.

Instead of the covering D, I may use a cord-stitch round the edge of each corner of the slate, as shown in Fig. 3.

Having thus fully described my invention, what I claim as new, and desire to secure by Letters Patent, is—

As a new article of manufacture, a paper frame composed of broad and narrow strips of paper or pasteboard forming the side and end bars, secured together by means of double lapping joints and cement, and the joints covered with leather or other soft material, substantially as described.

In testimony that I claim the foregoing as my own I here affix my signature in presence of two witnesses.

ORLANDO M. POND.
